NOISE SUPPRESSOR CIRCUIT

Walter van B. Roberts, Princeton, N. J., assignor
to Radio Corporation of America, a corporation
of Delaware

Application June 17, 1937, Serial No. 148,627

10 Claims. (Cl. 250—20)

My present invention relates to noise silencing circuits, and more particularly to receivers utilizing noise suppressors.

One of the main objects of this invention is to provide a noise silencer circuit in which the silencing action takes place when an interfering voltage of only slightly greater amplitude than that of the desired signal is received; the distinguishing feature of the present silencer circuit arrangement is the use of a multi-electrode tube as a diode detector which has its detecting quality controlled by the potential on a grid of the tube.

The novel features which I believe to be characteristic of my invention are set forth in particularity in the appended claims; the invention itself, however, as to both its organization and method of operation will best be understood by reference to the following description taken in connection with the drawing in which I have indicated diagrammatically several circuit organizations whereby my invention may be carried into effect.

In the drawing:

Fig. 1 shows a superheterodyne receiver embodying one form of the invention, and

Fig. 2 illustrates a modification of the silencer circuit.

The invention will best be explained with reference to Fig. 1 which shows, for the sake of illustration, a conventionalized superheterodyne receiver including a stage of intermediate frequency amplification whose gain is automatically controlled in accordance with signal strength. The receiver is generally of the type disclosed and claimed in my copending application Serial No. 80,497, filed May 19, 1936.

The receiver comprises, in general, a radio frequency amplifier 1, a converter 2, an I. F. amplifier 3 and a second detector D. A signal source A feeds collected signals to the amplifier 1, and the latter will include means for tuning it through a desired signal frequency range. The signal source A may be the usual grounded antenna circuit; radio frequency distribution line; or even the collector used on mobile vehicles such as automobiles. The amplified signals are fed to the tunable input circuit of the converter 2. It will be understood that the converter may be of the combined local oscillator-first detector type employing a pentagrid converter tube of the 2A7 type, or separate tunable first detector and local oscillator tubes may be used. In any case, it is to be understood that the tunable circuits of the radio frequency amplifier, the first

detector and the local oscillator networks will have the rotors of their variable tuning condensers mechanically arranged for uni-control.

The I. F. output of converter 2 is transmitted to one, or more, stages of I. F. amplification; therefore the numeral 3 is to be understood as designating a network which may include one or more amplifier tubes tuned to the operating I. F. The last I. F. output circuit 4 is coupled to the I. F. input circuit 5 of the second detector, or audio demodulator tube D. It is to be understood that the coupling transformer M₁ has its primary and secondary circuits fixedly resonated to the operating I. F. Similarly the primary and secondary circuits 4 and 5 of the coupling transformer M₂ are resonated to the operating I. F.

In Fig. 1 a triode D is used as a diode detector in combination with condenser K and resistance Q. The anode and cathode of tube D constitute the diode elements, while the grid 6 is used to control the internal resistance of the diode. A diode tube S is employed for the purpose of squelching the detecting action of detector D whenever the voltage across the transformer secondary winding L exceeds a predetermined value. A battery B₂ of low voltage may be included between the grid and cathode of tube D to maintain the grid normally somewhat positive, so as to reduce the internal resistance of the diode circuit to a value low enough to permit linear detection. This battery, however, is not essential to the squelching action of the circuit.

A second battery B₁ which is adjustable in value, is used to adjust the bias on diode S so that no current flows through it unless the voltage across coil L is greater than the maximum peak voltage of the desired signal. If, however, an interfering disturbance, such as for example is created by automobile ignition systems, sets up a transient voltage across coil L which is substantially greater than the desired signal, current will flow through diode S and set up a voltage across resistor R. If sufficient in intensity, this last voltage will make the grid 6 of detector tube D sufficiently negative with respect to its cathode to prevent any flow of current through the detector. Condenser C, shunted across resistor R, is chosen as small as possible so that the time required to build up the squelch voltage across resistor R will be small. Resistor R is preferably large, so that the interfering voltage will create a maximum voltage across R. The time constant RC is chosen great enough to maintain the squelching action for the duration of the interfering transient voltage, but, on the

other hand, not so great as to keep the detector inoperative for an unnecessary length of time.

The best values of R and C for any particular installation are best determined, however, by trial. In the absence of interfering voltages the operation of the circuit is quite conventional, and both the audio output and AVC potentials may be obtained from the detector resistor Q as shown. The AVC bias is applied through lead 10 and filter resistor 11 to the I. F. amplifier signal grid. Of course the AVC bias can be applied to the networks 1 and 2 as well. The AVC action is well known and need not be described.

In order to demonstrate the rapidity with which the detector is rendered inoperative as the voltage across coil L increases beyond the predetermined value, the following calculations have been made. Let us suppose that source B_1 has been so adjusted that $(B_1 - B_2)$, the total bias across diode S , is slightly greater than the maximum peak voltage of the desired signal. Let E represent an interfering voltage which is greater than this total bias. Then, assuming the internal resistance of diode S small compared to R , the rectified voltage across R will be very nearly $E - (B_1 - B_2)$. The total negative bias on the grid of the detector is, therefore, $E - B_1$.

If, now, the tap T is located at a point on the coil L where the voltage is a fraction F of the total voltage across the coil, the voltage impressed upon the detector is FE . It is well known that no current will flow in the detector if this voltage FE is less than the product of the grid bias and the amplification constant μ of the tube. Thus, the result is obtained that the detecting action will be squelched when the interfering voltage is appreciably greater than given by the equation

$$E = B_1 \frac{\mu}{\mu - F}$$

From this equation it will be seen that if the amplification constant of the tube is considerably greater than unity, it will make very little difference where the tap T is located; so that if desired it may be connected to the top of the coil. In any case it will be seen that the value of voltage E which produces a complete squelch of the detector circuit, is only a small percent greater than the predetermined value $(B_1 - B_2)$ if B_2 is small compared to B_1 . This latter is the normal condition as B_1 will usually be set to 10 volts, or more, in order to take care of the rather large signal voltages developed in the modern receiver.

In case it is desired to have the adjustment of the voltage B_1 take place automatically, and in accordance with the received signal strength, the circuit of Fig. 2 may be used. This circuit may be identical with that of Fig. 1 in every way, except in the method for obtaining the bias voltage for diode S . In my copending application Serial No. 108,427, filed Oct. 30, 1936, Patent No. 2,115,876, May 3, 1938, there is disclosed and claimed the automatic adjustment of the bias on the squelch diode. In Fig. 2, an auxiliary diode P is employed in conjunction with a high resistance M and a large capacity N to provide a positive potential on the cathode of diode S substantially equal to the modulation peaks of the desired signal. The time constant of network MN should not, however, be so large that abnormal voltage across M produced by interference voltages will persist unduly after the cessation of the interference. On the other hand, N should be large enough so that the bias on S will increase appreciably only after squelch bias has been gen-

erated across R by a strong interference signal. The inherent capacity X of the diode, or auxiliary capacity if desired, together with condenser C , divides the alternating voltage across diode P so that a lesser alternating voltage exists across diode S than the bias thereon. This reduction of the alternating voltage across S under normal circumstances prevents its drawing any current. This reduction of voltage should, of course, be sufficient to prevent drawing current even when consideration is taken of the fact that the anode of S is maintained slightly positive by the source B_2 . If the grid source B_2 is omitted it will not be necessary to insure any particular amount of reduction in the alternating voltage across diode S . For this reason it is preferable to use as the detector, a tube whose detecting qualities are satisfactory without requiring any positive bias on the grid.

In both Figs. 1 and 2 a certain amount of signal voltage may reach the detector tube grid through the distributed capacity of diode S , or by actual capacity as at the point x in Fig. 2. This however, merely assists in the detecting action of the detector, and is too small appreciably to affect the squelching action when the grid becomes strongly negative. Indeed, the aforesaid distributed capacity effects may be augmented by auxiliary capacity for the purpose of improving the detection action, provided that the alternating voltage thus introduced to the grid is not sufficient to interfere with satisfactory squelching action. It will be realized that while a triode detector is shown for the sake of simplicity, other tubes having suitable characteristics, such as pentodes, may be used. The connections are the same in either case, except that the screen must be connected to a suitable positive voltage if a pentode, or tetrode, is used.

While I have indicated and described several systems for carrying my invention into effect, it will be apparent to one skilled in the art that my invention is by no means limited to the particular organizations shown and described, but that many modifications may be made without departing from the scope of my invention, as set forth in the appended claims.

What I claim is:

1. A detector system comprising a multi-electrode tube having its plate and cathode connected to a common signal input circuit as a rectifier, said tube including a control grid in the electron stream between the cathode and plate, a second rectifier connected to said input circuit to produce rectified current in proportion to the excess of input voltage above a predetermined level, and a connection from the control grid of said first tube to the said second rectifier to impress rectified voltage from the latter on the grid.

2. A detecting system in accordance with claim 1, wherein a third tube is connected to said input circuit and second rectifier automatically to determine the said predetermined level.

3. A method of operating a signal detector of the type including a tube having at least a cathode, anode and a control electrode disposed in the electron stream between the cathode and anode, which includes impressing signals between the cathode and anode for rectification, rectifying alternating current energy, representative of interference noise, above a predetermined amplitude, and impressing the rectified noise energy upon the said control electrode in a sense to render the first rectification inefficient.

4. A method of operating a signal detector of the type including a tube having at least a cathode, anode and a control electrode, which includes impressing signals between the cathode and anode for rectification, rectifying alternating current energy, representative of interference noise, above a predetermined amplitude, impressing the rectified noise energy upon the said control electrode in a sense to render the first rectification inefficient, and controlling said second rectification in response to signal amplitude variation, and in a sense to prevent the second rectification until the said predetermined amplitude is exceeded.
5. In combination with a source of signals and a load circuit, a detector tube including at least a cathode, anode and control electrode, a signal input circuit coupled to the detector anode and cathode, means electrically connected to the anode and cathode for developing a rectified voltage from signal voltage in said input circuit, a rectifier having an alternating current input circuit in which exists alternating current energy impressed on said detector anode and cathode, means in circuit with the rectifier for developing a unidirectional voltage from said alternating current energy, and means for impressing the unidirectional voltage on said control electrode in a sense to decrease the rectification efficiency of said detector cathode and anode.
6. In combination with a source of signals and a load circuit, a detector tube including at least a cathode, anode and control electrode, a signal input circuit coupled to the detector anode and cathode, resistor means electrically connected to the anode and cathode for developing a rectified voltage from signal voltage in said input circuit, a rectifier having an alternating current input circuit in which exists alternating current energy impressed on said detector anode and cathode, resistor means in circuit with the rectifier for developing a unidirectional voltage from said alternating current energy, and means for impressing the unidirectional voltage on said control electrode in a sense to decrease the rectification efficiency of said detector cathode and anode.
7. In combination with a source of signals and a load circuit, a detector tube including at least a cathode, anode and control electrode, a signal input circuit coupled to the detector anode and cathode, means electrically connected to the anode and cathode for developing a rectified voltage from signal voltage in said input circuit, a rectifier having an alternating current input circuit in which exists alternating current energy impressed on said detector anode and cathode, means in circuit with the rectifier for developing a unidirectional voltage from said alternating current energy, means for impressing the unidirectional voltage on said control electrode in a sense to decrease the rectification efficiency of said detector cathode and anode, a signal amplifier coupled to said signal input circuit, and means for controlling the amplifier gain with said rectified signal voltage.
8. In combination with a source of signals and a load circuit, a detector tube including at least a cathode, anode and control electrode, a signal input circuit coupled to the detector anode and cathode, means electrically connected to the anode and cathode for developing a rectified voltage from signal voltage in said input circuit, a rectifier having an alternating current input circuit in which exists alternating current energy impressed on said detector anode and cathode, means in circuit with the rectifier for developing a unidirectional voltage from said alternating current energy, means for impressing the unidirectional voltage on said control electrode in a sense to decrease the rectification efficiency of said detector cathode and anode, said alternating current input circuit being the same as said signal input circuit, and means actuated by signal amplitudes below a desired level to render the said rectifier inoperative.
9. In combination with a source of signals and a load circuit, a detector tube including at least a cathode, anode and control electrode, a signal input circuit coupled to the detector anode and cathode, means electrically connected to the anode and cathode for developing a rectified voltage from signal voltage in said input circuit, a rectifier having an alternating current input circuit in which exists alternating current energy impressed on said detector anode and cathode, means in circuit with the rectifier for developing a unidirectional voltage from said alternating current energy, means for impressing the unidirectional voltage on said control electrode in a sense to decrease the rectification efficiency of said detector and anode, means for adjustably connecting the anode of the detector tube to said signal input circuit, and said alternating current input circuit being said signal input circuit.
10. In combination with a source of signals and a load circuit, a detector tube including at least a cathode, anode and control electrode, a signal input circuit coupled to the detector anode and cathode, means electrically connected to the anode and cathode for developing a rectified voltage from signal voltage in said input circuit, a rectifier having an alternating current input circuit in which exists alternating current energy impressed on said detector anode and cathode, means in circuit with the rectifier for developing a unidirectional voltage from said alternating current energy, and means for impressing the unidirectional voltage on said control electrode in a sense to decrease the rectification efficiency of said detector cathode and anode, and additional means for preventing rectification of alternating current energy below a predetermined amplitude by said rectifier.

WALTER VAN B. ROBERTS.
